(57) **CLAIM**

The ornamental design for a container and closure, substantially as shown and described.

DESCRIPTION

FIG. 1 is a side-elevational view of a container and closure embodying our new design, with the opposite side-elevational view being substantially a mirror image thereof;

FIG. 2 is a rear elevational view of the design;

FIG. 3 is a top plan view of the design;

FIG. 4 is an upper, perspective view of the design;

FIG. 5 is a lower, perspective view of the design;

FIG. 6 is a side-elevational view of a further embodiment of the design, with the opposite side-elevational view being substantially a mirror image thereof;

FIG. 7 is a rear elevational view of this embodiment of the design;

FIG. 8 is a top plan view of this embodiment of the design;

FIG. 9 is an upper, perspective view of this embodiment of the design;

FIG. 10 is a lower, perspective view of this embodiment of the design;

FIG. 11 is a side-elevational view of a further embodiment of the design, with the opposite side-elevational view being substantially a mirror image thereof;

FIG. 12 is a rear elevational view of this embodiment of the design;

FIG. 13 is a top plan view of this embodiment of the design;

FIG. 14 is an upper, perspective view of this embodiment of the design;

FIG. 15 is a lower, perspective view of this embodiment of the design;

FIG. 16 is a side-elevational view of a further embodiment of the design, with the opposite side-elevational view being substantially a mirror image thereof;

FIG. 17 is a rear elevational view of this embodiment of the design;

FIG. 18 is a top plan view of this embodiment of the design;

FIG. 19 is an upper, perspective view of this embodiment of the design; and,

FIG. 20 is a lower, perspective view of this embodiment of the design.
